TREE HOLDER

Filed Nov. 25, 1927

Harry E. Butler INVENTOR.

UNITED STATES PATENT OFFICE

HARRY E. BUTLER, OF NEWTON, MASSACHUSETTS

TREE HOLDER

Application filed November 25, 1927. Serial No. 235,483.

This invention relates to devices for supporting trees such as those used at Christmas and for decorative purposes.

It is the chief object of the invention to devise an article of this character which will be convenient to use, will present a pleasing appearance, and which still can be manufactured economically.

The nature of the invention will be readily understood from the following description when read in connection with the accompanying drawings, and the novel features will be particularly pointed out in the appended claims.

15 In the drawings,

Figure 1 is a plan view of a holder constructed in accordance with this invention, some of the parts being shown as broken away;

20 Fig. 2 is a side elevation, partly in cross-section, of the device shown in Fig. 1;

Fig. 3 is a cross-sectional view on the line $a-a$, Fig. 1;

25 Figs. 4 and 5 are side and plan views, respectively, of the upper end of one of the arms which grip the tree trunk; and

Fig. 6 is a plan view of the clasp which locks the device in its tree holding position.

The device shown includes four upright 30 metal arms 2, each provided at its upper end with an inturned extremity 3 which is pointed or toothed, as clearly shown in Figs. 2 and 4.

35 Preferably these arms are arranged in two pairs, the members of each pair being integral with each other and formed by bending a strip of metal into a U-shape, these two U-shaped members then being secured together at their lower ends by a stud 4, Fig. 2, shaped to provide an upwardly extending prong.

Secured to each of the arms 2 at a point intermediate its length is an inclined leg 5, one leg being provided for each arm, and the lower ends of the legs being spread apart so 45 that they serve both as braces and also as supports for the arms. The lower ends of these legs are removably secured to a base 6 which preferably consists of a small mat or rug made of linoleum or other suitable material. As shown in the drawings, the base 6

has four split studs or snap fasteners 7 secured thereto, and the lower end of each leg 5 is turned outwardly and is provided with an aperture to receive the fastener 7.

Encircling the arms 2 immediately below their connection with the legs 5 is a locking ring or clasp 8 which may conveniently be made of heavy relatively stiff wire provided with rubber sleeves 9 to bear against the arms 2, the sections of the wire on which the sleeves are mounted being straight.

In using the device the lower part or butt portion of the tree trunk is inserted between the arms 2 and the end face of the butt rests on the horizontal portions of the arms and is held in a centered position by the prong 4. It will be observed that the tree is supported by the lower portions of the arms, and if it is fairly heavy its weight will tend to depress all four of the arms 2. If the tree is small, as for example, of the size commonly used in a home for a Christmas tree, this depressing movement may be produced by grasping the butt of the tree and pressing it down into the holder. The lowering 50 movement of the arms produced in this manner will cause the upper ends of the inclined legs 5-5 to swing inwardly toward each other, as will be evident from an inspection of Fig. 2, the lower ends of the legs being supported by the base 6 against spreading movement. This, in turn, will force the teeth 3 at the upward 55 extremities of these arms into the sides of the tree trunk. As this action occurs the clasp 8 drops down on the arms 2 by gravity and locks them securely in their tree gripping position. It should be noted that the U-shaped members which include the arms 2 are slightly wider at their lower ends than at their central portions. In other words, 60 that they taper gradually so that as the clasp 8 slides downwardly it soon strikes a point where it sticks and locks the arms in their gripping relationship.

Most of the trees with which a device of this character is used are relatively small so that it is necessary to push them down into the holder in order to cause the holder to grip them. Consequently, in order to re- 65

lease such a tree it is simply necessary to slide the clasp 8 upwardly, thus permitting the upper ends of the arms 2 to spring outwardly and release the tree trunk. It can then be lifted out of the holder.

It will now be evident that the invention provides a tree holder of a very simple construction which can be manufactured economically and which will support the tree firmly in an upright position. The holder can be made in any suitable size and an individual holder will support and grip a considerable variety of sizes of tree trunks. The base or mat 6 can be decorated appropriately so that the entire device will present an attractive appearance.

While I have herein shown and described a preferred embodiment of any invention, it is contemplated that the invention may be embodied in other forms without departing from the spirit or scope thereof.

Having thus described my invention, what I desire to claim as new is:

1. In a tree holder, the combination of a plurality of upwardly extending arms having parts connected together at the lower ends of said arms, and forming a support for the lower end of a tree butt, said arms having teeth at their upper ends to engage the sides of the tree trunk, inclined legs supporting said arms, and means for supporting said legs against spreading.

2. In a tree holder, the combination of a plurality of upwardly extending arms connected together at their lower ends to provide a support for the lower end of a tree butt and being spaced around said butt, said arms having inwardly directed teeth at their upper ends to engage the sides of the tree trunk, inclined legs supporting said arms and fastened to the arms at points intermediate their length, a support for limiting the spreading movement of said legs, and a locking clasp encircling said arms and slideable vertically on them.

3. In a tree holder, the combination of a plurality of upwardly extending arms connected together at their lower ends to provide a support for the lower end of a tree butt and being spaced around said butt, said arms having inwardly directed teeth at their upper ends to engage the sides of the tree trunk, inclined legs supporting said arms and fastened to the arms at points intermediate their length, and a mat having means for detachably fastening the lower ends of said legs thereto.

4. In a tree holder, the combination of two substantially upright U-shaped members arranged at right angles to each other and connected together at their lower ends to form a support for the lower end of a tree butt, said arms being spaced around the tree trunk and the upper ends of said arms having inwardly directed teeth to penetrate the sides

of the trunk, inclined legs secured, respectively, to said arms at points intermediate their length, a base for connecting the lower ends of said legs together, and a locking clasp slideable on said arms below their point of connection with said legs.

5. In a tree holder, the combination of a plurality of upwardly extending arms having parts connected together at the lower ends of said arms and forming a support for the lower end of a tree butt, said arms having teeth at their upper ends to engage the sides of the tree trunk, inclined legs fastened to said arms and supporting the arms, and a locking clasp encircling said arms and slideable vertically on them.

HARRY E. BUTLER.
